MACHINE FOR REMOVING AND REPLACING METAL PARTS OF TRAIN-PIPE COUPLINGS.

1,252,676.

Specification of Letters Patent.

Patented Jan. 8, 1918.

Application filed October 23, 1916. Serial No. 127,151.

To all whom it may concern:

Be it known that we, WILLIAM D. FAIDLEY, Jr., residing at Clifton Forge, Alleghany county, Virginia, JOHN W. MORRIS, residing at Iron Gate, Alleghany county, Virginia, and SAMUEL A. PATTERSON, residing at Clifton Forge, Alleghany county, Virginia, citizens of the United States, have invented certain new and useful Improvements in Machines for Removing and Replacing Metal Parts of Train-Pipe Couplings, of which the following is a specification.

This invention relates to mechanism for detaching the metal parts of worn out train pipe couplings, especially the coupling heads, nipples and clamping bands carried by the opposite ends of the hose sections comprising such train pipe or air brake couplings, and for applying such metal parts to new hose sections. Heretofore when a hose section has become so worn as to be of no further use, the whole coupling has been discarded, although the metal coupling head, nipple and clamping bands are by no means unfit for further service. It is the aim of this invention to provide a machine for removing such metal parts from the old hose sections and for attaching them to new hose sections so that they may be again utilized.

The coupling head and nipple are fastened to the opposite ends of the hose section by clamping bands or rings having spaced outwardly turned flanges at their ends secured together by bolts bridging the space between said flanges. These clamping bands or rings must be removed before the coupling head and nipple can be separated from the end portions of the hose section, and the machine embodying the invention is equipped with means for doing this as the first step in the removal of the metal parts of the coupling. Means are also provided for holding the hose section while the coupling head and nipple are either withdrawn therefrom or applied thereto.

The invention will be first hereinafter described in connection with the accompanying drawings, which constitute part of this specification, and then more specifically defined at the end of the description.

In the accompanying drawings, wherein similar reference characters are used to designate corresponding parts throughout the several views:

55

Figure 1 is a side elevation of a machine constructed substantially in accordance with the present invention.

Fig. 2 is a plan view of the same.

Fig. 3 is a right hand end elevation of the 60 machine.

Fig. 4 is a vertical section on the line IV—IV of Fig. 1.

Fig. 5 is a detailed plan view of the means for cutting the bolts which hold the clamp- 65 ing band on the coupling.

Fig. 6 is a side view of the same.

Fig. 7 is a detailed view in section of the preferred form of tool for withdrawing the 70 nipples from the hose sections.

Fig. 8 is an end view of said tool.

Figs. 9 and 10 are side and end views of the expanding clutch carried by said tool.

Fig. 11 is a plan view of the tool for gripping the coupling head.

75

Fig. 12 is a side view of the same.

Fig. 13 is a detailed perspective view of the adjustable lug on said tool.

Fig. 14 is a similar view of one of the tools for removing the loosened clamping 80 bands from the hose sections simultaneously with the removal of the coupling heads and nipples.

Fig. 15 is a plan view of the hose gripping portion of the machine, showing auxiliary 85 means for holding the hose near the ends thereof, so that hose sections which have been very badly worn in the middle or separate end pieces of hose may be firmly held while the metal parts are withdrawn from 90 them.

Fig. 16 is a side view of the parts shown in Fig. 15.

Fig. 17 is a sectional view on the line XVII—XVII of Fig. 15.

95

Fig. 18 is a detailed perspective view of another auxiliary means for holding the end portions of the hose sections.

Fig. 19 is a similar view of a tool for putting on an air brake coupling head.

100

Fig. 20 is a detailed perspective view of a tool for putting on a steam coupling head.

Fig. 21 is a longitudinal section of another form of nipple-removing tool, and Fig. 21^a is an end view of the same.

- A table 1, which carries certain parts of the machine, is mounted upon suitable supports 2 and 3 at opposite ends thereof, the supports 2 at one end extending up through the table, as at 4, and supporting the pivot 5 of a lever 6 for operating the reciprocating knife 7 which is used for cutting the bolts 8 holding the clamping bands 9 around the hose sections. Said lever 6 is operated by a bell-crank lever 8 pivoted at 9 between a pair of longitudinal bars 10 arranged below the table 1, one end of said bell crank lever being connected to the lever 6 by a pitman 11 while the other end of said lever 8 is connected to the piston rod 12 of a compressed air cylinder 13 located on a platform 14 at the base of the table. Any suitable means (not shown) may be employed for controlling the reciprocating movement of the piston rod 12 for moving the knife 7 through the instrumentality of the bell crank lever 8, pitman 11 and lever 6. At one side of the knife 7 there is a depending guide 15 working in a slot 16 in the table. Another slot 17 enters from one side of the table and terminates adjacent the knife, and into this slot 17 the hose 52 is introduced, as shown in Fig. 5, when the bolt 8' is to be cut. When the hose is in position in the slot 17 as shown in this figure, the clamping band 9' is arranged above the top surface of the table and the middle portion of the bolt is disposed below the knife, so that when said knife descends it will cut through said middle portion of the bolt thus releasing the end portions or flanges 18 of the clamping band from one another. During the cutting operation the bolt 8 is supported upon a beveled lug 19 projecting above the top surface of the table 1 and having a vertical face 20 arranged substantially in vertical alignment with the flat side of the knife 7. The opposite face of the lug 19 is inclined, as at 21, Fig. 6. The bolt 8' also rests upon a beveled laterally extending lug 22 on a sliding member 23 fitted in a recess 50 in the table 1 and normally held in the position shown in Figs. 5 and 6 by a spring 24. When the knife descends its beveled edge, after passing through the bolt 8', enters between the lugs 19 and 22 and forces the sliding member 23 away from the fixed lug 21, thereby spreading the flanges 18 on the clamping ring 9' to some extent. As the knife completes its downward stroke the head 25 comes in contact with the flanges 18 and forces them still farther apart as they are moved down along the inclined face 21 of the lug 19 and the correspondingly inclined opposite face 26 of the lug 22. After this operation the clamping band 9' will be loose enough to be readily removed when the

coupling head and nipple are taken off by the mechanism presently described. After being removed the clamping band is in condition to be used again for holding a nipple or coupling head on a new hose section.

Said hose section is then placed across the stationary jaw 27 of a holding clamp arranged on the table 1, and the supplemental movable member 28 of said clamp is forced down upon it by means of compressed air apparatus including a cylinder 29 supported on the back of the machine, a piston rod 30 working in said cylinder, an intermediately pivoted lever 31 connected at one end to said piston rod, and a link 32 connected to the other end of the lever 31 and to the movable jaw 28. It will be understood that any suitable means (not shown) may be employed for controlling this compressed air apparatus.

At one side of the clamping jaws 27 and 28 a sliding block 33 is mounted on guides 34 to be moved toward and away from said clamping jaws. The movement of said block 33 is effected by a lever 35 pivoted at 36 between the bars 10, a link 37 connected at one end to the lever 35, another lever 38 pivoted at 39 between the bars 10 and connected to the other end of the link 37, another link 40 connected at one end to the lever 38, another lever 41 pivoted at 42 between the bars 10 and connected to the other end of the link 40, and a piston rod 43 working in a compressed air cylinder 44 and connected to the lever 41, as clearly illustrated in Fig. 1.

At the other side of the clamping jaws 27 and 28 a block 45 is mounted to slide on guides 46 toward and away from said jaws, and said block 45 is reciprocated by means of a lever 47 pivoted at 48 between the bars 10, and a link 49 connected at one end to the lever 47 and at the other end to the lever 38. From the arrangement of levers shown and described, it will be seen that the outward movement of the piston rod 43 will cause the blocks 33 and 45 to move in opposite directions away from the clamping jaws 27 and 28, while the reverse movement of the piston rod 43 will advance the blocks 33 and 45 toward said clamping jaws.

As illustrated in Figs. 1, 7 and 8 the block 45 carries a tool 50 adapted to enter the nipple 51 on the adjacent end of the hose section 52 on the advance movement of said block 45. Said tool 50 is provided with an expanding clutch comprising two members 53 hinged together at 54 and adapted to project through slots 55 in the tool, as shown in Fig. 7, for engaging the inner end of the nipple 51 so that when the block 45 is moved away from the clamping jaws 27 and 28, the nipple will be withdrawn from the hose section 52 which is clamped between said jaws. The two members 53 of the clutch are nor-

5 mally held folded, as in Fig. 9, by a spring 56, and when in this position the clutch is capable of passing through the nipple. After the tool 50 is introduced into the end 5 of the hose section past the nipple, as shown in Fig. 7, a wedge 57 is advanced between said members 53 of the clutch by means of a hand lever 58 pivoted at 59 on the tool 50 and having its inner end 60 working in the 10 slot 61 in an extension 62 of the wedge 57 which is mounted to slide inside of the tool 50. A coiled spring 63 is arranged about the extension 62 of the wedge 57 and abuts at opposite ends against a shoulder 64 on said 15 wedge and a shoulder 65 on the tool for assisting in the advance of the wedge between the members of the clutch at the proper time. The members 53 of the clutch have teeth 66 on their outer edges for gripping the inner end of the nipple 51, and said members also have lugs 67 on their inner edges for limiting the outward movement thereof by engaging the ends of the slots 55, as shown in Fig. 7. The tool 50 may have 20 longitudinally extending grooves 68 in its side to afford free escape of air when said tool is thrust into the nipple.

As shown in Figs. 1, 11, 12 and 13, the 25 block 33 has detachably connected thereto a tool 69 mounted upon rollers 70 running on the top surface of the table 1. This tool 30 69 has a pair of upwardly projecting lugs 71 and 72 between which the coupling head 73 may be inserted so that when the block 35 33 is moved away from the clamping jaws 27 and 28, said coupling head will be withdrawn from the hose section which is gripped between said jaws. In order to 40 adapt the tool 69 to fit different sizes of coupling heads, the lug 72 is made removable and reversible so as to vary the distance between it and the fixed lug 71. To this end the lug 72 is provided with a laterally extending portion 74 which with the reduced 45 base 75 of the lug fits a slot 76 in the tool 69. The lug 72 also has a threaded portion 77 to pass through the slot 76 and receive a nut 78 for securing the lug in either one of its positions. It will be readily understood that 50 when the nut 78 is loosened on the threaded portion 77, the lug may be raised until its reduced base 75 and lateral projection 74 are removed from the slot 76, and that when the lug is turned around and its base 75 is 55 seated in the slot with the projection 74 at the opposite side, the distance between the lugs 71 and 72 will be changed. Both of the lugs 71 and 72 may be provided with curved 60 portions or recesses, as indicated at 79, in Fig. 13, to prevent the coupling heads from being injured.

One of the tools illustrated in Fig. 14 is carried by each of the reciprocating blocks 33 and 45, as shown in Fig. 1. Each of these 65 tools comprises a leaf 82 fastened to the

block, a hinged portion 81 and depending fingers 83 at the free end of said hinged portion. The hinged portion 81 is of angular formation so as to raise it above the tools 50 and 69, and is notched at 81^a to avoid interfering with the hand lever 58. The fingers 83 are designed to embrace the hose section 52 and engage the clamping bands 9', which have been loosened as already explained, whereby said clamping bands are removed 75 from the hose section simultaneously with the removal of the nipple and coupling head when the blocks 33 and 45 are moved away from each other. The fingers 83 may be adjusted, as suggested at 84, for fitting different sizes of hose sections.

As illustrated in Figs. 15, 16 and 17, auxiliary hose gripping means may be provided for insuring the proper holding of hose sections which have become so worn out in 85 the middle as to be unfit for being firmly gripped between the clamping jaws 27 and 28. This auxiliary gripping means may also be used for holding separate end portions of hose, as where the hose sections have become 90 entirely worn through at the middle. This auxiliary gripping means comprises a pair of claws arranged at each side of the clamping jaws 27 and 28. One claw 85 of each 95 pair is stationary, while the other claws 86 are mounted to slide across the table 1 in guides 87. The movable claws 86 of each pair may be moved in unison by means of eccentrics 88 on a countershaft 89 journaled in brackets 90 on the back of the machine 100 and rotated by means of an arm 91, a link 92 connected at one end to said arm, a lever 93 connected to the other end of the link and intermediately pivoted at 94 to a bracket 95 depending from the table 1, a link 96 105 connected to the other end of the lever 93, a bell crank lever 97 connected to the link 96 and pivoted at 98 to an extension of the pivot 39 for the lever 38, and a link 99 connecting the other end of the bell crank lever 110 97 with the lever 41 operated by the piston rod 43 in the cylinder 44. It will thus be seen that during the movement of the blocks 33 and 45 toward the clamping jaws 27 and 28, the movable claws 86 will be advanced 115 toward the fixed claws 85 for gripping the end portions of the hose section.

When the hose sections are short, the tool 100, Fig. 18, may be used instead of the claws 85 and 86. This tool 100 has a base 120 101 adapted to fit in the guides 87, so that said tool may be placed at the side of the clamping jaws 27 and 28 adjacent the nipple removing tool. Each tool 100 carries a U-shaped blade 102 adapted to be inserted 125 between the end of the hose section and the wrench engaging flange 80 on the nipple and when so arranged will positively hold the hose section while the nipple is being withdrawn. It will be understood, of course, 130

that the flat face of the blade 102 is engaged with the end of the hose section.

In Fig. 19 is illustrated a tool 103 adapted to be attached to the block 33 in place of the tool 69 when it is desired to attach an air brake coupling head to a new hose section. The tool 104 illustrated in Fig. 20 is designed for attachment to the block 33 when a steam pipe coupling head is to be attached to a new hose section. The tool 50 may be used for attaching nipples to new hose sections as well as for removing nipples from old hose sections as already described, the operation of attaching the nipples being simply the reverse of that for removing them. The new hose section to which nipples and coupling heads are to be attached may be held between the clamping jaws 27 and 28 in the same manner as the old hose section when the metal parts are removed therefrom.

The modified form of nipple-engaging tool 110 shown in Figs. 21 and 21^a differs from the tool 50, Figs. 7 and 8 in having one fixed clutch tooth 111 and one movable clutch tooth 112, whereas the tool 50 has both clutch teeth movable. The movable clutch tooth 112 is pivoted at 113 to the body of the tool 110 and is operated by means of a hand lever 114 pivoted at 115 and normally pressed by a spring 116. The tool 110 is flat on the sides and is especially adapted for use with crushed or mashed nipples.

Having thus described our invention what we claim as new and desire to secure by Letters Patent is:

1. The combination with means for holding the hose section of a train pipe coupling, of a reciprocating tool adapted to enter the nipple on the end of said hose section, an expanding clutch carried by the tool and comprising two jaws projecting from opposite sides of the tool, resilient means for normally holding said jaws closed to permit the clutch to enter the nipple, a wedge mounted to slide in the tool and adapted to spread the jaws apart for gripping the nipple on the inside whereby the same may be drawn out of the hose section when the tool is moved away from the hose holding means, and means for actuating said wedge from the outside of the tool when the latter is in the nipple.

2. The combination with means for holding the hose section of a train pipe coupling, of a reciprocating tool adapted to enter the nipple on the end of said hose section, an expanding clutch carried by the tool and comprising two jaws projecting from opposite sides of the tool, resilient means for normally holding said jaws closed to permit the clutch to enter the nipple, a wedge mounted to slide in the tool and adapted to spread the jaws apart for gripping the nipple on the inside whereby the same may be

drawn out of the hose section when the tool is moved away from the hose holding means, means for actuating said wedge from the outside of the tool when the latter is in the nipple, and resilient means for automatically moving said wedge between the jaws when said actuating means is released. 70

3. The combination with means for holding the hose section of a train pipe coupling, of a reciprocating tool adapted to enter and grip the inside of the nipple on the end of said hose section for drawing it out of the same, said tool having a longitudinally extending groove in its outer surface for the escape of air as it enters the nipple. 75

4. The combination with means for holding the hose section of a train pipe coupling, of a table, a block movable along the table toward and away from said holding means, a tool attached to said block at one end, 85 rollers running on the table and supporting the other end of the tool, and means on the tool for engaging the metal end piece of the coupling for drawing the same out of the hose section when the block is moved away 90 from said holding means.

5. The combination with means for holding the hose section of a train pipe coupling, of a reciprocating member, and a pair of spaced lugs on said member for engaging 95 the coupling head for removing the same from the hose section when said member is moved away from said holding means, one of said lugs being adjustable toward and away from the other lug for the purpose 100 specified.

6. The combination with means for holding the hose section of a train pipe coupling, of a reciprocating member, and a pair of spaced lugs on said member for engaging 105 the coupling head for removing the same from the hose section when said member is moved away from said holding means, said lugs having rounded portions presented to the coupling head for the purpose specified. 110

7. The combination with means for holding the hose section of a train pipe coupling, of a reciprocating member, a fixed lug on said member, an adjustable lug having an offset at one side of its base, the member 115 having a slot into which the base of the adjustable lug and its offset fits, and means for fastening said lug in said slot with the offset at either side for varying the distance between the adjustable lug and the fixed lug. 120

8. The combination with means for holding the hose section of a train pipe coupling, comprising a fixed jaw and a movable jaw, of an intermediately pivoted lever, means attached to one end of the lever for swinging the same, and a link connecting the other end of the lever to the movable jaw. 125

9. In a machine of the character described, the combination with reciprocating means for removing the metal end piece from 130

the hose section of a train pipe coupling, of a fixed U-shaped member to fit between the end of said hose section and metal end piece for holding the hose section during

5 the removal of said end piece.

10. In a machine for removing the coupling heads and nipples from the hose sections of train pipe couplings, the combination with mechanism for withdrawing the
10 clamps which secure the coupling heads and nipples to the hose sections, of means for drawing said coupling heads and nipples out of the hose sections, said mechanism and means being connected whereby they operate
15 simultaneously.

11. In a machine of the character de-

scribed, the combination with means for holding the hose section of a train pipe coupling, of a member movable toward and away from said holding means, means on 20 said member for engaging the metal end piece of the coupling for drawing the same out of the hose section when said member is moved away from the holding means, of mechanism pivotally mounted on and movable with said movable member whereby said mechanism and means operate simultaneously. 25
